BALANCER

Reinhold A. Norling, Aurora, Ill., assignor to Independent Pneumatic Tool Co., Chicago, Ill., a corporation of Delaware

Application March 16, 1931. Serial No. 523,166

13 Claims. (Cl. 242—107)

This invention relates to counter-balances, particularly adapted for use with portable power driven tools, such as electric drills and the like, for suspending such tools from an overhead support above the places of work, whereby the tools when not in use will be elevated out of the way, yet be within reach for being drawn down to the work.

In my co-pending applications, Serial Nos. 10 523,164 and 523,165, both filed March 16, 1931, I have shown and claimed counter-balances in which the cable carrying reels or drums each have a single spring therein for controlling the turning of the reels and for holding the tools suspended at varying elevations, as when stopped at different distances from the reel.

In accordance with my present invention, I provide the reel with a plurality of springs so constructed and arranged that the reel may make a greater number of turns in the use of the device before the springs are completely wound up and thus permit the tool or other load attached to the cable or the reel to move up and down to a greater extent than with the single spring arrangement.

A further object of my invention is to provide novel means for connecting the springs, whereby their tension may be adjusted simultaneously.

30 A further object of my invention is to provide a simple and compact structure and one which will effectively serve the purpose for which it is designed.

Other and further objects of my invention will appear from the following specification taken in connection with the accompanying drawings, in which

Fig. 1 is a side view, with parts broken away and in section, of a balancer constructed in accordance with my invention;

Fig. 2 is a vertical sectional view, with parts in elevation, taken on line 2—2 of Fig. 1;

Fig. 3 is a bottom plan view taken on line 3—3 of Fig. 2, to show the cable guard;

Fig. 4 is a vertical sectional view taken on line 4—4 of Fig. 2;

Fig. 5 is a side view of another form of balancer to be hereinafter described; and

Fig. 6 is a vertical sectional view taken on line 6—6 of Fig. 5.

In the drawings, 1 indicates the reel or drum of the balancer, 2 the shaft on which the reel is rotatably mounted, and 3 the support for the shaft and housing for the reel. The support comprises two parts, an upper part 4 and a lower

part 5. The upper part 4 is in the form of a casing covering the upper half of the reel. The lower part 5 is in the form of a U-shaped member straddling the lower half of the reel. The parts 4, 5 are secured together where they meet by screws or bolts 6, 6 engaging lugs on semi-cylindrical bosses 7, 8 which provide bearings for the adjacent ends of the shaft 2. The latter fits within its bearing at one side of the frame. A sleeve 9 has a rotative fit in the bosses at the other end of the shaft, with the sleeve surrounding the shaft, as shown.

The reel 1 is made hollow and located within the same are two flat coil springs 10, 11. The springs are arranged in side by side relation and both surround a sleeve 12 loosely mounted on the shaft 2. The sleeve 12 has a length to extend through both springs and is common thereto. The inner ends of both springs are connected to the sleeve 12 by keys 13, 13, one for each spring. The outer end of the inner spring 10 is connected to the inner surface of the reel 1 by a rivet or pin 14. The outer end of the outer spring 11 is similarly connected to an inwardly extending flange 15 at the periphery of a barrel 16 located on the outer side of said spring. The barrel 16 has a hub portion 17 extending laterally outward therefrom into the sleeve 9 and keyed thereto by a pin 18 as shown. By this connection, the barrel 16 will be turned with the sleeve 9 in the rotation thereof by a worm or screw 19 to adjust the tension of the springs. The barrel 16 is a stationary in the operation of the balancer, being turned only when adjusting the tension of the springs. With the barrel 16 in the form of a casting, the sleeve 9 is made of better material to resist the wear thereon in the action of the worm.

The worm 19 is rotatably mounted in the upper boss 7 on the side of the casing 4 at the sleeve 9 and has teeth 20 which engage teeth 21 on the sleeve 9. The worm is provided at one end with a tool receiving socket 22 whereby the worm may be turned to adjust the tension of both springs through the outer one 11. This is made possible having both springs connected through the sleeve 12. The other end of the worm 19 seats against a plate 23 at the inner end of the socket or cavity in which the worm is mounted to prevent rotation of the worm to loose the tension of the springs.

The annular wall 24 of the reel is provided on its outer side with a spiral groove 25 which leads the cable 26 on and off the reel in the

turning thereof. One end of the cable is attached to the reel and the other end is attached to the frame 3. This provides a loop in the cable outside of and below the reel to support a sheave 27 carried in a block or frame 28 from which depends a swiveled hook 29.

To permit attachment of the cable to the frame, the upper member 4 thereof is provided with a lug 30 having a number of holes through which the cable end is inserted and fastened as shown in Fig. 1. This manner of attachment is claimed in my co-pending application Serial No. 523,165. The cable is attached to the reel at one end by being inserted through holes 31 in the reel, as shown in Fig. 4. The loop 32 formed in the cable at these holes receives the end of the cable, as shown. This manner of attachment is claimed in my co-pending application, Serial No. 523,164.

20 The cable carrying wall or portion 24 of the reel is tapered or inclined to the axis of the reel, as provided by the shaft 2, so as to balance the load on the cable at its different distances from the reel in the use of the device. This 25 tapered feature is claimed broadly in my co-pending application, Serial No. 523,164.

With two springs for the reel, the latter can make twice as many turns before the springs are wound up, and the tool or load suspended from the cable may travel twice as far up and down before the springs are wound up. This is so because one spring acts in advance of the other, in the tensioning of the springs to counteract the load on the cable.

30 An attaching hook 33 is secured to the upper portion of the frame 3 above the reel for connecting the balancer to an overhead support, either fixed or movable, as the installation may require.

40 A cable guard 34 is fastened by screws 35 to the under side of the upper part 4 of the frame to keep the cable from improper winding in the groove 25. To keep the springs from buckling sideways, I provide plates 36, 37 on opposite 45 sides of the inner spring 10. The plate 36 is between the springs. The barrel 16 provides a cover over the outer side of the outer spring. The reel has an annular seat 38 on its inner side for the spring 10. The plate 37 is held in place by a shoulder 39 on the inside of the reel on the outer side of said plate. A shoulder 40 also in the reel provides a seat for the plate 36. The reel has a hub 41 to support the reel 35 on the portion of the shaft 2 not encompassed by the two springs.

50 The bottom member or bar of the U-frame 5 is provided on its under side with an abutment 42 for the sheave 27. This abutment is wide enough to serve as a stop for the sheave in any 55 shifted position of the sheave along the axis of the reel.

60 The balancer shown in Figs. 5 and 6 is generally similar to the balancer shown in Figs. 1 and 2, except with respect to the reel and the 65 abutment for the sheave carried in the loop of the cable, and such other details as will be herein referred to.

70 The reel 43 of the balancer shown in Figs. 5 and 6 has its cable carrying portion 44 straight, that is, substantially parallel to the axis of the reel, instead of being tapered or inclined as in the balancer shown in the preceding figures. Reel 43 is mounted in a frame 45 on a shaft 46, the same as before. By reason of the short 75 hub 47 of the reel, it is pressed tight on the shaft

46. The end of the shaft at the hub turns in the bearing 48 provided therefor in the frame 45, while the opposite end of the shaft turns in the hub 17^a of the barrel 16^a. Springs 10^a and 11^a are located in the reel about the shaft 46 and are connected together and to the reel 43 and barrel 16^a, respectively, the same as before, with the barrel turnable about the axis of the reel to adjust the tension of the springs, by a worm action, the same as in Figs 1 and 2. The reel 43 is provided at its ends with peripheral flanges 49, 49 between which the layers of the cable 50 are confined in winding on the reel. The cable carrying portion 44 is provided in its outer surface with a suitable groove or channel 51 to accommodate the cable and serve as a guide to lead the first layer of the cable across the reel in the turning of the same. The two springs 10^a, 11^a provide for a greater number of turns of the reel than with a single spring and thus permit a longer cable to be employed, thereby allowing for a greater distance of travel of the tool or load suspended from the cable to and from the reel. With a greater number of turns allowed for the reel before the springs 100 are wound up, the cable may wrap in successive layers on the reel, as shown in Fig. 6. The springs can have their tension adjusted to suspend the tool or load either close to the reel as when the cable is entirely wound thereon or 105 the spring can be adjusted that the load can be suspended at a considerable distance from the reel. The lower member 52 of the frame 45 is provided with an abutment 53 below the reel for the sheave 54 in the loop of the cable as shown 110 in Fig. 6. A pair of relatively long bolts 55, 55 are inserted through the lower member 52 of the frame on opposite sides of the cable 50 and extend outward from the frame on that side of the reel on which the cable winds and 115 unwinds. Collars 56, 56 are mounted on the bolts and serve to prevent the cable from climbing when the first layer reaches an end of the reel. The collars when the cable strikes the same will crowd the cable over and thus start 120 it on the next layer.

With the type of reel shown in Figs. 5 and 6, the balancer will only support the tool at a certain point high or low according to the adjustment of the springs. The load, however, can 125 be moved a considerable distance without undue exertion thereon, due to the fact that the two springs exert only half pressure for each revolution of the reel.

Where parts in Figs. 5 and 6 are the same as 130 in Figs. 1 and 2 like reference numerals are employed to designate them.

The provision of two springs in the reel in both forms of balancers is an important feature of my invention, as well as is the feature of adjusting the tension of both springs simultaneously through one of them. These features enable a simple and compact balancer to be made with a relatively long range of movement up and down for the load on the cable. The frames 3 and 45 being made in two parts, as shown, with the parts connected together at the bearings for the shaft provides a form of construction which simplifies the assembling of the devices.

The details of structure and arrangement of parts shown and described may be variously changed and modified without departing from the spirit and scope of my invention except as pointed out in the appended claims.

I claim as my invention:

1. A counter-balance of the character described, comprising a reel adapted to have a cable wound thereon, a supporting shaft for the reel, a plurality of springs, one acting through the other, for turning the reel in a direction to wind the cable thereon, and means independent of said shaft for adjusting the tension of the springs, said means including a sleeve rotatably mounted on the shaft and providing a common connector for the inner ends of the springs. 80
2. A counter-balance of the character described, comprising a reel adapted to have a cable wound thereon, a supporting shaft for the reel, a plurality of springs for turning the reel in a direction to wind the cable thereon, and means independent of said shaft for adjusting the tension of the springs simultaneously, said means including a sleeve rotatably mounted on the shaft within the springs and providing a common connector for the inner ends thereof. 85
3. A counter-balance of the character described, comprising a reel adapted to have a cable wound thereon, a supporting shaft for the reel, a plurality of springs for turning the cable in a direction to wind the reel thereon, said reel having a cable carrying portion tapered or inclined to the axis of the reel, and means independent of the shaft for adjusting the tension of the springs, said means including a sleeve rotatably mounted on the shaft within the springs and providing a common connector for the inner ends thereof. 90
4. A counter-balance of the character described, comprising a reel adapted to have a cable wound thereon, a support for the reel including a shaft on which the reel is rotatably mounted, a normally stationary member rotatably carried by the support in concentric relation to said shaft, two springs for turning the reel in a direction to wind the cable thereon, said springs having their outer ends connected to the member and reel, respectively means for turning the member for adjusting the tension of the springs, and a sleeve rotatably mounted on the shaft and providing a common connector for the inner ends of the springs whereby the latter may be tensioned simultaneously. 95
5. A counter-balance of the character described, comprising a reel including a shaft on which the reel is rotatably mounted adapted to have a cable wound thereon, a support for the reel, a normally stationary member rotatably carried by the support in concentric relation to said shaft and having a laterally extending annular flange thereon, two flat spiral springs for turning the reel in a direction to wind the cable, one spring being located within said flange and having its outer end connected thereto, the other spring being located in the reel and having its outer end connected to the reel, a sleeve rotatably mounted on the shaft and providing a common connector for the inner ends of the springs, and means for turning said member to adjust the tension of said springs. 100
6. A counter-balance of the character described, comprising a shaft, a support therefor, a reel on said shaft, a normally stationary barrel mounted on the shaft at one side of said reel and having an annular flange extending into the reel, two flat spiral springs surrounding said shaft for turning the reel, one spring being located in the barrel and having its outer end connected to the flange thereof, the other spring 105
- being located in the reel and having its outer end connected to the reel, a sleeve rotatably mounted on the shaft and providing a common connector for the inner ends of the springs, and means for turning the barrel to adjust the tension of the springs. 110
7. A counter-balance of the character described, comprising a shaft, a support therefor, a reel on said shaft, a barrel at one side of the reel and having a hub on said shaft, two coil springs surrounding the shaft for turning the reel, said springs having their outer ends connected to the barrel and reel, respectively, a member on the shaft and connecting the inner ends of the springs, a sleeve fixed to the hub of the barrel and having worm teeth, and a worm carried by the support and engaging the teeth of the sleeve for turning the barrel for adjusting the tension of the springs. 115
8. A counter-balance of the character described, comprising a reel, a support therefor, said support consisting of two parts, one part being in the form of a casing enclosing one half of the reel, the other part being in the form of a U-shaped frame straddling the other half of the reel and secured to the first part, said parts where they are secured together having bearing bosses, a shaft for the reel supported in said bosses, spring means for turning the reel for winding a cable thereon, and an abutment for 120 the load on the cable carried by the U-shaped part of the support. 120
9. A counter-balance of the character described, comprising a reel, a support therefor, said support consisting of two parts, one part being in the form of a casing enclosing one half of the reel, the other part being in the form of a U-shaped frame straddling the other half of the reel and secured to the first part, said parts where they are secured together having bearing bosses, a shaft for the reel supported in said bosses, spring means for turning the reel for winding a cable thereon, and a guard for the cable secured to the casing part on the under side thereof. 125
10. A counter-balance of the character described, comprising a reel, a support therefor, said support consisting of two parts, one part being in the form of a casing enclosing one half of the reel, the other part being in the form of a U-shaped frame straddling the other half of the reel and secured to the first part, said parts where they are secured together having bearing bosses, a shaft for the reel supported in said bosses, spring means for turning the reel for winding a cable thereon, the cable being connected at one end to the reel and the other end to the casing part of the support to provide a loop in the cable exterior of the support, a load carrying element carried by the cable by having a sheave in the loop thereof, and an abutment for the sheave on the U-shaped part of the support. 130
11. A counter-balance of the character described, comprising a reel, a supporting shaft for the reel, a plurality of springs, one acting through the other to turn the reel, and means independent of the shaft for adjusting the tension of the springs simultaneously, said means including a common connector for the inner ends of the springs rotatably mounted on said shaft, said reel having a cable carrying portion arranged substantially parallel to the axis of the reel. 135
12. A counter-balance of the character de- 140

scribed, comprising a reel, a supporting shaft therefor, and a plurality of springs for turning the reel, and means independent of the shaft for adjusting the tension of the springs, said 5 springs being connected to act one through the other so that each will exert a pressure on the reel in one revolution thereof in proportion to the number of springs associated with the reel, said means including a sleeve rotatably mounted 10 on the shaft within the springs and providing a common connector for the inner ends thereof.

13. A counter-balance of the character de-

scribed, comprising a reel, a support therefor, a plurality of springs, one connected with the reel and acting one through the other for turning the reel, said reel having a cable carrying portion arranged substantially parallel to the axis of the reel, and a pair of members carried by the support on opposite sides of the cable adjacent where it leaves the reel and extending outward from the support for causing the cable to wind in successive layers on the reel.
